US00D892122S

(12) **United States Design Patent** (10) Patent No.: **US D892,122 S**
(45) Date of Patent: ** Aug. 4, 2020

(54) **DOCK**(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)(***) Term: **15 Years**(21) Appl. No.: **29/633,341**(22) Filed: **Jan. 12, 2018****Related U.S. Application Data**

(63) Continuation of application No. 29/569,968, filed on Jul. 1, 2016, now Pat. No. Des. 808,971, which is a continuation of application No. 29/501,654, filed on Sep. 5, 2014, now Pat. No. Des. 760,721.

(51) LOC (12) Cl. ..... **14-02**(52) U.S. Cl. USPC ..... **D14/434**(58) **Field of Classification Search**

(57) CLAIM

The ornamental design for a dock, as shown and described.

DESCRIPTION

FIG. 1 is a front perspective view of a dock showing the claimed design;
 FIG. 2 is a rear perspective view thereof;
 FIG. 3 is a top view thereof;
 FIG. 4 is a bottom view thereof;
 FIG. 5 is a left side view thereof;
 FIG. 6 is a right side view thereof;
 FIG. 7 is a rear view thereof; and,
 FIG. 8 is a front view thereof.

The broken lines in the figures show portions of the dock that form no part of the claimed design.

The shade lines in the figures show contour and not surface ornamentation.
